DESIGN FOR A DIRECTIONAL SIGNAL LAMP

Frank A. Stafford, Conway, and Charles L.
Farrens, Clarinda, Iowa

Application July 22, 1940, Serial No. 93,826

Term of patent 3½ years

To all whom it may concern:

Be it known that we, Frank A. Stafford, a citizen of the United States, resident of Conway, Taylor County, Iowa, and Charles L. Farrens, a citizen of the United States, and resident of Clarinda, Page County, Iowa, have invented a new, original, and ornamental Design for a Directional Signal Lamp, of which the following is a specification, reference being had to the accompanying drawing, forming a part thereof.

Fig. 1 is a side elevational view of our directional signal lamp showing our new design.

Fig. 2 is a top view thereof.

Fig. 3 is an enlarged end view thereof as viewed from the left of Fig. 1.

We claim:

The ornamental design for a directional signal lamp, substantially as shown.

FRANK A. STAFFORD.
CHARLES L. FARRENS.
